UNITED STATES PATENT OFFICE.

OTTO JOHNSON, OF PORTSMOUTH, NEW HAMPSHIRE

HIGHWAY GRADE-LEVEL CROSSING FOR RAILWAYS.

Application filed August 7, 1924. Serial No. 730,556.

To all whom it may concern:

Be it known that I, OTTO JOHNSON, a citizen of the United States of America, and a resident of Portsmouth, county of Rockingham, and State of New Hampshire, have invented certain new and useful Improvements in Highway Grade-Level Crossings for Railways, of which the following is a full and clear specification.

10 The object of this invention is to provide an inexpensive and durable structure which will compel an approaching driver to slow up his vehicle before crossing the tracks and which will induce the driver to come 15 to a full stop, or nearly a full stop, prior to crossing the tracks, to give him ample opportunity for determining whether or not it is safe to go ahead; and a further object 20 is to provide means for insuring against the car stopping on the railway-bed after the driver decides to make the crossing, as more fully hereinafter set forth.

In the drawing is represented a miniature perspective view of a railway crossing embodying my invention in its preferred form.

In the preferred form of my invention, I divide the highway into two one-way driveways, and in the right-hand driveway, adjacent the railway-bed, I construct an 30 elevated platform A whose entrance is inclined at B to form a ramp, the inclination being gradual to enable the approaching car to readily climb to the top of the platform. The exit-end of the platform is likewise provided with a downwardly-inclined ramp C which terminates at or close to the adjacent railroad-rail, this ramp having an angle of inclination which is sufficient to 35 carry an unbraked car, by its own momentum, entirely across the railway tracks when the car is started down the incline, thereby insuring against stoppage of the car on the tracks, whether or not the car be under power.

40 It will be observed that an approaching driver will be required to drive up upon the platform before crossing the railway-tracks. The platform will be preferably sufficiently long to accommodate at least one car and 45 possibly long enough to accommodate more than one. The driver will, of course, be compelled to move slowly in going up upon and traversing the platform, and this slow- 50 ing-up of the car will give the driver an opportunity to study the situation. The top of the platform is constructed so as to

induce the driver to come to a full stop; for this purpose, I concave the top surface of the platform to provide a depression in which the car may rest when it is stopped. 60 This depression requires that the car shall make a slight ascent before leaving the platform, thus insuring not only against the car prematurely leaving the platform, but also requiring a deliberate action on the 65 part of the driver in order to go forward. When the car is once over the exit-crest, the exit-ramp will, as heretofore stated, insure the car a sufficient momentum to carry it clear across the railroad-bed, whether or 70 not the clutch be in, unless, of course, the driver applies the brake with sufficient force to counteract the propulsion given the car by the ramp.

75 It is desirable that the side edges of the platform be provided with curbs D to insure against the car running off the platform, altho it will be understood that, even tho a car should run off the platform, it would not cause serious damage, since it is believed 80 that it will not be necessary to build the platform higher than a foot or so. I prefer building the platforms of cement or concrete, preferably reenforced, so that they 85 will have a maximum durability, notwithstanding the fact that they will necessarily be in the open and therefore be subject to all kinds of weather conditions. It is desirable also that the top surface of the platform shall be corrugated or ribbed transversely, to not only interfere with speeding 90 over the platform, but also to assist in bringing the car to a stop in the saddle portion of the platform.

95 It will be observed that the platforms are staggered with reference to each other and that the inner vertical wall of one is virtually in the same vertical plane with the inner wall of the other platform, so that, should a driver decide to break the traffic 100 regulations that will necessarily govern the use of my crossing and attempt to skirt the platform, he will have to take a zigzag course across the tracks, which would slow him up probably about as much as he would 105 be slowed up in driving over the platform. However, to still further discourage any attempts to get over the railway without traversing the platform, I may place obstructions E across the railroad-bed in line with 110 the inner walls of the platforms, these obstructions being in the form of elevations,

as shown, or depressions, or any other devices that would render it difficult or impossible for a driver to cross the roadbed obliquely at that point. These barriers will, of course, not be of such nature as to interfere with the free and safe passage of the trains.

It will be further understood that slight changes may be necessary to accommodate my invention to the natural topography of some crossings. For instance, if the land at the opposite side from the propulsion-ramp inclines upwardly, this land will have to be cut away sufficiently to permit the car to come clear of the railway-bed under the momentum imparted to it by the ramp.

What I claim as new is:

1. A highway grade-level crossing for railway-roadbeds in which the highway is divided into two one-way driveways, the right-hand driveway being provided with an elevated platform long enough to receive a car and having an inclined approaching-section and an inclined exit-section, the latter terminating near the adjacent railway-rail, each platform having its top surface depressed, for the purpose set forth.

2. A highway grade-level crossing for railway-roadbeds in which the highway is divided into two one-way driveways, the right-hand driveway being provided with an elevated platform long enough to receive a car and having an inclined approaching-section and an inclined exit-section, the latter terminating near the adjacent railway-rail, each platform having its top surface 35 depressed, for the purpose set forth.

3. A highway grade-level crossing for railway-roadbeds in which the highway is divided into two one-way driveways, the right-hand driveway being provided with an elevated platform long enough to receive a car and having an inclined approaching-section and an inclined exit-section, the latter terminating near the adjacent railway-rail, obstructions being placed in the railway-bed across the same substantially in line with the inner vertical walls of the platforms, for the purpose set forth.

In testimony whereof I hereunto affix my signature.

OTTO JOHNSON.
